UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

SPECIFICATION forming part of Design No. 11,710, dated March 30, 1880.

Application filed February 12, 1880. Term of patent 3½ years.

To all whom it may concern:

Be it known that I, HENRY HORAN, of East Orange, in the county of Essex and State of New Jersey, have invented a new and original 5 Design for Carpet, of which the following is a specification.

This invention relates to a new and original design for carpets, oil-cloths, and similar fabrics.

10 It consists in the novel grouping and configuration of figures hereinafter more fully described.

The accompanying photograph illustrates a face view of a carpet having my new design.

15 On the background of the carpet are placed three groups, A B C. Group A consists of two branches, a a, of buds and leaves at the bottom of the field, and with the budded ends extending toward each other. Group B is composed of four leafy branches, a a a a, at 20 the top of the field; and group C is composed of two centrally-placed branches, a a, of leaves and buds with the ends pointing toward each other.

I claim—

25 The design for a carpet, consisting of the lower and upper groups, A B, and central group, C, substantially as shown.

HENRY HORAN.
